UNITED STATES PATENT OFFICE.

THOMAS LONG, OF BOSTON, MASSACHUSETTS, ASSIGNOR TO THE CONSOLIDATED FASTENER COMPANY, OF PORTLAND, MAINE.

MECHANISM FOR OPERATING MACHINES FOR ATTACHING BUTTONS, &c.

SPECIFICATION forming part of Letters Patent No. 700,790, dated May 27, 1902.

Application filed May 24, 1900. Serial No. 17,796. (No model.)

To all whom it may concern:

Be it known that I, THOMAS LONG, a citizen of the United States, residing at Boston, in the county of Suffolk and Commonwealth of Massachusetts, have invented a new and useful Improvement in Mechanisms for Operating Machines for Attaching Buttons or for other Purposes, of which the following is a full specification.

10 My invention relates to mechanisms for operating machines for attaching buttons or for other purposes which have an intermittent motion controlled by the operator and which while having a continuously-revolving driving-wheel driven by a belt or other means are arranged to make but one revolution at each pressure of the operator's lever; and it consists in a new and improved mechanism whereby this result is surely accomplished without 20 danger of more than one revolution being made.

My improved mechanism could readily be applied to any power-machine having an intermittent motion controlled by the operator; 25 but I have shown it as applied to a button-setting machine, as set forth in Letters Patent No. 608,693, issued August 9, 1898. In this mechanism for operating machines for attaching buttons or for other purposes referred to the operation of setting a button is 30 accomplished by means of foot-power, and I have adapted my improved mechanism to same so that the operation is performed by power by the pressing of a small treadle, which 35 causes the machine to make a revolution.

Referring to the accompanying drawings, wherein like letters represent like parts, Figure 1 is a side elevation of my improved mechanism for operating machines for attaching buttons or for other purposes. Fig. 2 is a plan of driving mechanism. Fig. 3 is a horizontal section of mechanism for operating machines for attaching buttons or for other purposes on the line 3 3, Fig. 1. Fig. 4 is a vertical section on the line 4 4, Fig. 3, showing the driving-pulley in elevation. Fig. 5 is a vertical section on the line 5 5, Fig. 3, looking in the direction away from the driving-wheel. Fig. 6 is a vertical section on the line 6 6, Fig. 5, looking toward the back of the mechanism. Fig. 7 is a perspective view of

sliding dog. Fig. 8 is a vertical section on the line 8 8, Fig. 3, showing removable treadle in dotted lines. Fig. 9 is a plan of my removable treadle.

In the drawings, A is the frame of my mechanism; B, the bell-crank lever, by partial revolution of which motion is imparted to any machine supported on the frame A. An adjustable toggle-joint lever, having the arms C and C', is pivoted, respectively, to the bell-crank B and to the frame A at c. By straightening out this toggle C C' the bell-crank B is made to turn, and this straightening of the toggle I accomplish by the cam D, which turns with 60 the shaft E and bears against the roller c' on the arm C'. The toggle-joint C C' is held in its normal position by the spring a and is also provided with the dash-pot or buffer c², which strikes against the cam D as the 65 toggle flies back after the cam has made a revolution, and thus breaks the shock. I have also provided the removable treadle 70 C³, Figs. 8 and 9, which can be inserted in the bottom of the toggle C', a suitable treadle-pocket being provided for its reception and by which the machine can be operated by 75 foot-power independently of the power mechanism and whether the power mechanism is in operation or at rest. The advantage of 80 this construction lies in the fact that the machine can be operated either by foot or by power. Normally the power mechanism would be used; but it is oftentimes desirable to move the bell-crank lever less than a full movement—for instance, where an inspection of the 85 lower moving member of the mechanism operated by the toggle is desired or the parts carried by said member be changed, &c., at which time a full movement is not desirable, 90 and then the foot-power (the treadle C³) is operated to the extent desired without changing the position of the parts of the power mechanism. The presence of the treadle-pocket and the fact that the toggle-lever is 95 not positively connected to the power-driving mechanism make the structure especially desirable.

The cam D is fixed to the shaft E, which turns in suitable journals in the hangers F F', 100 secured to the frame A.

The driving-pulley G turns loosely on the

shaft E and carries in its hub the projecting pins or teeth g , which I preferably urge outward by the springs g' , but which may be solidly fixed to the hub.

- 5 On the opposite side of the driving-wheel G from the cam D is the sliding dog H. (Shown in perspective in Fig. 7.) This dog carries the key h , which slides in a keyway in the shaft and also projects from each end, as 10 shown. When the dog is forced toward the driving-wheel, its projecting key h engages with one of the pins or teeth g of the revolving driving-wheel, and the dog H, shaft E, and cam D are thus carried around with the 15 driving-wheel G. By the springs I bearing between the dog H and collar e, fixed to the shaft E, the dog H is constantly urged away from the pulley and toward the hanger F', which is provided with a cam-plate f on the side 20 next to the dog H. The greater part of the surface of the cam-plate f is in circular plane at right angles to the axis of shaft E; but it is provided with a depression f' , Fig. 6, in which one end of the projecting key h rests 25 when in normal position, being held therein by the springs I. The parts are so proportioned that when in its normal position the other end of the key h is just out of engagement with the pins or teeth g of the pulley 30 G; but when the dog H is slid along the shaft, so that the one end of the key h is engaged by one of the pins or teeth g , the other end of the key h is even with the plane surface 35 of the cam-plate f and is carried around on this surface for the greater part of a revolution or until it can drop or move into the depression f' , thus locking the dog H in its operative position. As shown, the entering side of the depression f' is sloped in order 40 that the key h may enter it easily; but the other side of the depression f' forms a shoulder f'' , against which the key h rests in its normal position. The key h is forced out 45 of the depression f' by the sliding ejector-rod O, which by means of the treadle J, rod K, rocker-lever L, lever M, rods n and N is given a sliding motion parallel to the shaft. The treadle mechanism is held in its normal 50 position by the spring l acting on the rocker-lever L, as shown. When the key h rests against the shouldered end of the depression f' , it also rests against the end of the ejector-rod O, and when the treadle is pressed by the operator's foot the rod O moves forward and 55 presses the key h out of the depression f' against the tension of the springs I, the latter causing the key h to remain in contact with the face of the cam f . When the end of the key h is flush with the surface of the 60 cam f , its other end engages with one of the pins or teeth g , and the key, dog, shaft, and cam D are carried around for a revolution until by means of the tooth-disengaging mechanism, consisting of the springs I, the dog H 65 is forced out of gear, the key h dropping again into the depression f' , where it will stay until the treadle is again pressed.

In addition to the springs I, I provide another tooth-disengaging mechanism or positive means of throwing the dog out of gear, 70 as follows: On the dog H, I provide a cam-lug h' , adapted to engage at the proper point of revolution with the cam P, rigidly attached to the hanger F', so that the dog, with key h , is thrown out of gear with the pins g and 75 g' into the depression f' . This tooth-disengaging mechanism provides a positive throw-out in case the springs I should break or weaken; but I have found that less shock is experienced by providing the said springs I as well. 80 Should the operator keep the treadle pressed down after a revolution has been made, the key h will simply bring up against the rod O, which will be projected out into the depression f' and supported by its shoulder f'' . 85 Another revolution cannot be made until the treadle is released and pressed again. When the treadle is released and the rod O withdrawn, it is necessary to turn the shaft slightly in order that the key h may rest 90 against the shoulder f'' again and opposite the end of the rod O, and this I preferably accomplish by the spring-pin R on the cam D, which bears against the roller c' , and thus urges the cam forward. This same result is 95 accomplished by the spring s , which exerts a constant pull on the crank-pin S, attached to the end of the shaft E. The mechanism is operative if the pins g are simply fixed teeth in the hub of the pulley G; but I preferably use the pin-springs g' in the hub of the wheel in case the treadle should be pressed at a time when one of the pins g is directly opposite the key h in the dog. In this event the pin will simply yield before the advancing 100 key h and slip past it, so that the next pin will engage with the key h .

It will thus be seen that by my improved mechanism a revolution of the cam, and only one revolution, can be made with each pressure of the treadle and that it is impossible for the cam to make a second revolution unless the treadle is released and pressed again.

I claim—

1. In mechanism for operating machines 115 for attaching buttons, or for other purposes, the combination of a constantly-driven mechanism; a toggle-joint lever; means for operating said lever, said means being normally out of operative connection with the driven 120 mechanism; and a treadle-actuated power stop mechanism for positively moving said means into operative connection with the driven mechanism, said mechanism automatically preventing a movement in excess of a 125 single revolution of the driven mechanism, regardless of the position of the treadle.

2. In mechanism for operating machines 130 for attaching buttons, or for other purposes, the combination of a constantly-driven mechanism; a toggle-joint lever; means for operating said lever, said means being normally out of operative connection with the driven mechanism; and a treadle-actuated power

stop mechanism for positively moving said means into operative connection with the driven mechanism, said connection being held substantially non-yielding during the 5 major portion of the revolution of the driven mechanism, said mechanism automatically preventing a movement in excess of a single revolution of the driven mechanism, regardless of the position of the treadle.

10 3. In mechanism for operating machines for attaching buttons, or for other purposes, the combination of a constantly-driven mechanism; a toggle-joint lever; means for operating said lever, said means being normally 15 out of operative connection with the driven mechanism; a treadle-actuated power stop mechanism for positively moving said means into operative connection with the driven mechanism; and means for automatically disengaging said connection at a predetermined 20 point in the revolution of the driven mechanism irrespective of the position of the position of the treadle.

25 4. In mechanism for operating machines for attaching buttons, or for other purposes, the combination of a constantly-driven mechanism; a toggle-joint lever, means for operating said lever, said means being normally out of operative connection with the driven 30 mechanism; a treadle-actuated power stop mechanism for positively moving said means into operative connection with the driven mechanism; and means for automatically disengaging said connection at a predetermined 35 point in the revolution of the driven mechanism irrespective of the position of the treadle, said means being operated at a plurality of points.

40 5. In a mechanism for operating machines for attaching buttons, or for other purposes, a toggle-joint lever having a treadle pocket or socket, a treadle in said socket and power-driven mechanism mounted to intermittently impart a movement to said lever, said mechanism being independent of and having no 45 positive connection with said toggle, whereby the lever may be moved independently by treadle or power-driven mechanism.

50 6. In a mechanism for operating machines for attaching buttons, or for other purposes, a treadle-actuated stop mechanism comprising a splined driving-shaft and a loose hub-toothed pulley on said shaft, in combination with an ejector and treadle-actuated sliding 55 keyed dog automatically held in operative position during the greater portion of the rotation of the shaft, and tooth-disengaging mechanism operating automatically regardless of the position of the treadle; substantially as 60 shown and described.

65 7. In a mechanism for operating machines for attaching buttons, or for other purposes, a treadle-actuated stop mechanism comprising a splined driving-shaft, and a loose hub-toothed pulley on said shaft, in combination with a sliding dog keyed to said shaft, springs for normally holding said dog out of engage-

ment with said pulley, a plate having a dog-receiving depression, a treadle-actuated ejector-rod O, and means for automatically disengaging said dog and pulley regardless of the position of the treadle, substantially as shown and described. 70

8. In a mechanism for operating machines for attaching buttons, or for other purposes, a stop mechanism comprising a splined driving-shaft, a loose hub-toothed pulley on said shaft, in combination with a sliding dog keyed to said shaft and having a cam-lug h', a cam-plate having a dog-receiving depression and a lug-engaging cam, and an ejector whereby said shaft makes one and but one revolution at each stroke of the ejector, substantially as shown and described. 75

9. In a mechanism for operating machines for attaching buttons, or for other purposes, a stop mechanism comprising a splined driving-shaft, a spring-actuated crank-pin s, and a loose hub-toothed pulley mounted on said shaft, in combination with a sliding dog keyed to said shaft and normally held in inoperative position, a cam-plate having a dog-receiving depression, and a treadle-actuated ejector-rod O, substantially as shown and described. 80 90

10. In a mechanism for operating machines for attaching buttons, or for other purposes, a toggle-joint lever and a roller c', thereon, in combination with a driven shaft, a cam fixed on said shaft, a spring-pin R slidable therein, a power stop mechanism for driving the shaft, comprising a loose hub-toothed pulley, a sliding keyed dog normally held in inoperative position, a cam-plate having a dog-receiving depression, and a treadle-operated ejector-rod, all substantially as shown and described. 95 100 105

11. In a mechanism for operating machines for attaching buttons, or for other purposes, a toggle-joint lever and a buffer C² carried thereby, in combination with a power-driven cam, said buffer being adapted to operate on the active face of said cam, substantially as shown and described. 110

12. In a mechanism for operating machines for attaching buttons, or for other purposes, a treadle-actuated stop mechanism comprising a splined driving-shaft, a loose pulley having spring-pressed teeth in its hub, in combination with an ejector and treadle-actuated sliding keyed dog normally held out of engagement with said teeth and automatically held locked in operative position thereto during the greater portion of the rotation of the shaft, and tooth-disengaging mechanism operating automatically regardless of the position of the treadle, substantially as shown and described. 115 120 125

In testimony whereof I have signed my name to this specification, in the presence of two subscribing witnesses, on this 13th day of April, A. D. 1900.

THOMAS LONG.
